UNITED STATES PATENT OFFICE.

ARTHUR E. SPENCER, OF LAKE CITY, FLORIDA.

FOOT-ACCELERATOR.

1,255,479.

Specification of Letters Patent.

Patented Feb. 5, 1918.

Application filed June 27, 1917. Serial No. 177,319.

To all whom it may concern:

Be it known that I, ARTHUR E. SPENCER, a citizen of the United States, residing at Lake City, in the county of Columbia and 5 State of Florida, have invented certain new and useful Improvements in Foot-Accelerators, of which the following is a specification.

This invention relates to an improved type 10 of foot accelerator for motor vehicles, the present embodiment of the invention being designed primarily for use on Ford automobiles, although its application need not be limited thereto.

15 The main object of the invention is to provide an attachment whereby one pressure of the foot will supply the required amount of gas for any load and at the same time furnish the needed amount of hot air to reduce to a minimum the consumption of gas.

20 Another object is to provide an attachment of this character operated by a single foot lever which is so connected that hot air is fed to the engine manifold simultaneously 25 on the opening of the gas throttle of the carbureter.

With the foregoing and other objects in view, which will appear as the description 30 proceeds, the invention resides in the combination and arrangement of parts and in the details of construction hereinafter described and claimed, it being understood that changes in the precise embodiment of the invention herein disclosed may be made within 35 the scope of what is claimed without departing from the spirit of the invention.

In the accompanying drawings:—

Figure 1 is a fragmentary side elevation 40 of an automobile showing the application of this invention,

Fig. 2 is an enlarged side elevation showing the carbureter and this improvement applied, and

Fig. 3 is a detail plan view of the carbureter and the improved parts applied thereto.

In the embodiment illustrated, an automobile is represented at A whose engine E is equipped with the usual carbureter C, the 50 throttle valve stem S of which is equipped with the common type of L-shaped crank L movable in a horizontal plane and having in the free end of its longer arm an eye which usually receives the down-turned end E' 55 of a hand actuated rod R whose control member is positioned contiguous to the steer-

ing wheel, not shown. The shorter arm of the crank L is equipped with a set screw or the like s adapted to abut a stop s' on the carbureter C to limit the movement of said 60 crank.

All of the parts so far briefly described are of common construction, the end E' of the rod R being usually received in the eye of the crank L whereby endwise shifting of 65 said rod by the operator will adjust the throttle valve by turning its stem S. When using this improved accelerator however, the end E' of the rod R is removed from the eye of the crank L and is received in an 70 arcuate slot 1 formed in a flat horizontal substantially triangular plate 2 which overlies the crank L. A fastening element in the form of a bolt 3 is passed through this plate 2 and through the eye in the crank L 75 while an additional bolt 4 passes through said plate and through the shorter arm of the crank. The plate 2 is as above stated, preferably of approximately triangular shape, two of its sides being positioned at 80 right angles to each other while its third side is curved to conform to the curvature of the slot 1, the latter being disposed concentric with the stem S.

In addition to the objects above described, 85 the plate 2 is formed with an aperture 5 with which is engaged one end of a coiled spring 6 which is connected at its other end with the fixed portion of the automobile shown at 7 and operates to return plate 2 and the 90 throttle valve actuating crank L after the same has been operated as will presently be described. The plate 2 also has an aperture 8 with which is engaged a chain 9 which connects said plate with a depending arm 95 10 of a rod 11, said rod 11 being connected at its front end with a crank rod 12 with which is connected a foot lever 13.

The rod 11 which is substantially L-shaped in form has the long arm thereof extending over and resting on a valve casing 14 which opens into the manifold M of the engine E and is controlled by the valve, the stem 15 of which projects through said casing and has an aperture therein through 100 which the depending arm 10 of rod 11 passes, so that when this rod is operated by the depression of the foot lever 13, this valve will be opened and simultaneously the throttle valve of the carbureter opened by means 105 of the connection of said rod arm 10 with the plate 2 by the chain 9.

This valve casing 14 communicates with the lower end of a cone-shaped hot air pipe 16 which is arranged in close proximity to the engine so that the air passing there-through is heated and enters the manifold in this heated condition, thereby operating to thin the mixture fed into the manifold thus reducing the gas consumption required for operating the engine.

10 From the above description it will be seen that a single depression of the foot lever 13 will cause the rod 12 to rock and thereby move rod 11 longitudinally causing the valve stem 15 to open the valve within the 15 casing 14 and at the same time to exert a pull on the chain 9 and thereby open the throttle valve of the carburetor so that hot air and gas will be simultaneously fed to the engine by a single depression of the foot 20 lever.

From the foregoing description, taken in connection with the accompanying drawings, the advantages of the construction and of the method of operation will be 25 readily apparent to those skilled in the art to which the invention appertains and while I have described the principle of operation of the invention together with the device which I now consider to be the best embodiment thereof, I desire to have it understood that the device shown is merely illustrative and that such changes may be made as are 30 within the scope of the claimed invention.

I claim:—
35 1. In a device of the class described, a valve operating lever, a slotted plate con-

nected therewith, an apertured valve stem, a foot pedal operatively connected therewith, and a connection between said slotted plate and said lever stem.

40

2. In a device of the class described, a valve, an apertured valve stem, a foot pedal operatively connected therewith, a valve operating lever, a rod connected to be operated by said lever, said rod having a right 45 angularly disposed arm extending through said apertured valve stem, and a connection between the free end of said arm and said valve.

3. A foot accelerator attachment for use 50 in connection with the throttle valve operating crank of a carburetor and the manifold control rod for said crank, said attachment comprising a plate to be secured to said crank, said plate having an arcuate 55 slot to be positioned concentric with the pivot of the crank, said slot being provided for the purpose of slidably connecting the aforesaid manual control rod with the plate, a foot actuated operating rod connected to 60 said plate, and a hot air supply valve for supplying air to the engine manifold also connected with said rod whereby a single pressure on said rod will operate to open said valve and actuate said plate.

65

In testimony whereof I affix my signature in presence of two witnesses.
